UNITED STATES PATENT OFFICE.

WILLIAM H. WALDRON, OF WASHINGTON, DISTRICT OF COLUMBIA.

MILITARY STOCK.

Application filed July 21, 1923. Serial No. 652,968.

To all whom it may concern:

Be it known that I, WILLIAM H. WALDRON, a citizen of the United States, residing at Washington, District of Columbia, have invented a Military Stock, of which the following is a specification.

My invention is an improvement in the manufacture of stocks and collars, and relates more especially to the provision of means by which to promote the stability of a military stock particularly while it is in use.

The conventional military stock of curvilinear form is made up of several plies of fabric stitched together at its edges and comprises a body portion with interlocking end tabs to which the draw-strings are attached, and although this stock in use is worn within the collar of the military coat and is therefore reinforced to some extent thereby it oftentimes crumples or sags down resulting not only in the discomfort of the wearer but also in the impairment of his neat appearance, the last mentioned plight being an important consideration to a military man.

This incapability of the stock to maintain its upright position is due in great measure to the instability of the material of which it is made, and of course it is undesirable to have the stock made of stiffer material than the fabric ordinarily employed or to stiffen it with extraneous means such as usually employed in connection with the neck-band of soft collars.

The primary object of my invention is to increase the stability of a military stock without increasing the thickness of the same or adding materially to the cost of its production, and I accomplish this in the present instance by providing the stock with longitudinal lines or rows of stitches closely arranged in connection with diagonal lines of cooperating trussing stitches, whereby a stock so made is effectively stiffened and will properly hold its shape when it is in use.

In the accompanying drawings, forming a part of this specification:

Fig. 1 is a perspective view of a military stock made in accordance with my invention.

Fig. 2 is an enlarged view of one end portion of the stock.

Fig. 3 is a similar view of the other end portion.

Fig. 4 is a plan view of a military stock

showing a single zig-zag line of trussing stitches.

Fig. 5 is a view illustrating the application of the invention to the neck-band of a fold-collar.

Like letters and numerals of reference indicate like parts in the several figures of the drawings.

My invention is applicable to any of the well known or prevailing styles of collars or stocks, which are as usual composed of several plies of fabric sewed together at the edges by lines of stitches 10, and in carrying out my invention such a collar or stock is provided with rows of longitudinal lines of stitches 11 spaced approximately close together for the full width of the stock or neckband of the collar and with diagonal lines of stitches 12 likewise extending nearly the full width of the stock or collar-neckband; whereby said longitudinal lines of stitches together with the diagonal lines of stitches combine to reinforce, brace, stiffen, or otherwise increase the stability of the stock or collar-neckband to prevent it from sagging, crumpling, breaking down, or in any other manner impairing its proper set when in use. I find that the arrangement of the diagonal or trussing lines of stitches 12 as shown in the drawings is most effective in securing the desired permanent upright set of the stock or collar-neckband; that is to say, by running these stitches in a zig-zag line from one end to the other of the stock or collar-neckband. There may be a single zig-zag line of trussing stitches 12, as shown in Fig. 4, but the article will be stiffened or braced to a greater extent by the additional lines of trussing stitches 13 shown in the drawings, these being disposed at opposite sides of said zig-zag line of stitches and parallel therewith, or arranged in V-form—direct and inverted—maintaining their diagonal direction.

As hereinbefore stated I have particularly in mind the feature of increasing the stability of a military stock of the conventional curvilinear form (Fig. 4) and comprising a body portion with tapered ends forming tabs a and a' and as this type of stock is provided with a transverse slot a^2 for the interlocking engagement of the tabs the longitudinal lines or stitches 11 and trussing stitches 12 and 13 are stopped at either side of said slot. In applying the stitches to the stock I prefer to use heavier thread for the

zig-zag line of stitches 12 than the thread used in running the horizontal lines of stitches 11 and the trussing stitches 13.

In Fig. 5 of the drawings I have illustrated the application of the invention to the neckband *b'* of a fold-collar *B*, and in this instance the longitudinal and diagonal or trussing lines of stitches will reinforce or brace the neckband in the same manner as for a military stock.

I claim:—

1. Means for increasing the stability of a military stock or neckband comprising substantially parallel rows of stitches running approximately the length of the stock or neckband and the full width thereof with shorter lines of stitches diagonally disposed to the aforementioned rows of stitches crossing the same and also extending approximately the full length and width of the stock or neckband, said diagonal lines of stitches being in different series disposed at opposite angles with respect to the longitudinal lines of stitches.
2. Means for increasing the stability of

a military stock or neckband comprising horizontal lines of stitches arranged approximately close together for nearly the full width of the stock or neckband, and cooperating zig-zag lines of trussing stitches also extending approximately the full width of the stock or neckband and crossing the horizontal lines of stitches.

3. A military stock or neckband having longitudinal rows of stitches arranged approximately close together for approximately the full width of the stock or neckband, a zig-zag line of trussing stitches running from one end portion of the stock or neckband to the other across said longitudinal lines of stitches approximately the full width of said stock or neckband, and additional shorter V-shaped lines of trussing stitches the vertices of the adjacent and corresponding V's being in lines substantially parallel to the length of the stock or neckband and of the superimposed V's in lines substantially perpendicular to the length of the stock or neckband.

WILLIAM H. WALDRON.
